UNITED STATES PATENT OFFICE

171,689

RADIO TELEVISION CABINET

Jack De Young, Grand Haven, Mich., assignor
to Zenith Radio Corporation, a corporation of
Illinois

Application July 23, 1953, Serial No. 26,105

Term of patent 7 years

(Cl. D56—4)

To all whom it may concern:

Be it known that I, Jack De Young, a citizen of the United States, residing at Grand Haven, in the county of Ottawa, State of Michigan, have invented a new, original, and ornamental Design for a Radio Television Cabinet, of which the following is a specification, reference being made to the accompanying drawings, forming a part thereof.

Figure 1 is a perspective view of a radio television cabinet showing my new design;

Figure 2 is a perspective view of the radio television cabinet with the image reproducer exposed and the radio and phonograph compartments opened; and

Figure 3 is a right side elevational view of the radio television cabinet.

The design of the side of the cabinet not shown is similar to the design of the side shown in Figure 3. The rear of the cabinet is unornamented.

It is understood that the shading of the lower doors indicates fabric extending over the entire door surface.

The dominant features of my design reside in the portions shown in full lines.

I claim:

The ornamental design for a radio television cabinet, substantially as shown and described.

JACK DE YOUNG.
